UNITED STATES PATENT OFFICE.

EDWIN L. GATTERER, OF JERSEY CITY, NEW JERSEY.

BOTTLE-HOLDER.

SPECIFICATION forming part of Letters Patent No. 752,968, dated February 23, 1904.

Application filed July 16, 1902. Serial No. 115,778. (No model.)

To all whom it may concern:

Be it known that I, EDWIN L. GATTERER, a citizen of the United States, residing in Jersey City, in the county of Hudson, State of New Jersey, have invented certain new and useful Improvements in Bottle-Holders, of which the following is a specification, reference being had to the accompanying drawings, forming a part hereof.

This invention relates to bottle holders or stands, and more particularly to holders or stands for irregularly-shaped bottles, such as the common flat nurser.

The object of the invention is to provide a simple frame adapted for conveniently receiving and holding such a bottle and having a relatively broad base, whereby the bottle is held in a substantially upright position, as for filling, without any liability of upsetting.

In the drawings, Figure 1 is a side view of the bottle-holder with the bottle held therein. Fig. 2 is a front view of the same, the outline of the bottle being indicated by dotted lines. Fig. 3 is a plan view of the holder without the bottle.

A nurser of the common form has been chosen for illustration and is indicated at A in the drawings.

The bottle-holder comprises a suitable frame B for receiving and holding the bottle and a relatively broad base C, over which the frame is supported by standards d, in order to rest the bottle with stability. The frame B may comprise a flat ring or band a, which is elliptical in shape to conform to the periphery of the bottle, and a lower or bottom support b for supporting the base of the bottle and preferably secured to the flat ring or band a by flat strips c. It is customary to provide the ordinary flat nursing-bottle with a vent-valve at the base thereof, and the lower or bottom support b may accordingly comprise a ring or band, which encircles the neck of the vent, as is clearly illustrated in the drawings.

The base C is preferably formed of a piece of wire bent into a circular shape and is of such a dimension that the frame B may be supported over the same in a manner to hold the bottle within the circumference of said base. The standards d, which are preferably

three in number, are secured to the base in any suitable manner, two of them being attached to the bottom support b, and the third or back standard being attached to the ring or band a. It will be obvious that the length 55 and position of these standards d will determine the position of the frame B with respect to the base C, and that the particular shape of the bottle will require slight variations in the position of the frame with respect to the base in order to bring the center of gravity of the bottle and its contents directly over the center of the base, this being of course the condition for greatest stability. The center of the band a and the center of the support b, 60 if both are projected upon the base C, should lie in the same line with the center of the base C; but the relative disposition of these three points upon said line will vary with the inclination of the frame B to the base C and 70 also with the position of the band a with respect to the support b.

The frame B and the standards d may be stamped out of a single piece of sheet metal and easily bent into the form above described, 75 and shown in the drawings. The ends of the standards d, which are of flat strips of metal, may then be bent around and soldered to the annular-shaped wire base C.

It will be obvious that instead of employing 80 sheet metal the bottle-holder may be constructed of wire, which is bent into the proper shape, and, furthermore, instead of constructing the holder from one piece of wire or metal the same may be formed of separate parts, 85 which are afterward fastened together. It will also be obvious that a bottle-stand constructed in this way will be almost impossible to overturn and that the bottle may be easily and quickly inserted and withdrawn from the 90 same.

These holders will be found most useful for 95 retaining the bottles while they are being filled with hot fluids, as well as while they are being rinsed out with scalding-hot water.

It will be evident that by changing the position of the frame B with respect to the base and by varying the shape of the retainer-band a a bottle-holder may be constructed which will be adapted to receive any bottle, what- 100

ever be its shape, and accordingly the invention is not to be considered as limited to bottle-holders for irregularly-shaped bottles.

I claim as my invention—

- 5 1. A bottle holder or stand comprising a ring or band and a bottom support secured to said ring or band for receiving and holding a bottle, a relatively broad base, and standards for supporting said ring or band and bottom support upon said base, substantially as described.
- 10 2. A bottle holder or stand adapted to receive and hold a bottle having a vent-valve at the bottom thereof, said holder or stand comprising a flat ring or band for encircling the bottle, a second ring or band for supporting the base of the bottle and encircling the neck of said vent, a relatively broad base for supporting said rings or bands, and standards upon said base arranged to support the bottle and rings or bands centrally over the base, substantially as described.
- 15 3. A bottle holder or stand adapted to receive and hold a bottle having a vent-valve at the bottom thereof, said holder or stand comprising

ing a flat ring or band for encircling the bottle, a second ring or band for supporting the base of the bottle and secured to the first ring or band, a relatively broad base for supporting said rings or bands, the center of said base being on a line between the centers of said rings or bands, and standards upon said base to support the bottle and rings or bands, substantially as described.

4. A bottle holder or stand comprising a ring or band and a bottom support secured to said ring or band for receiving and holding a bottle, a wire bent so as to form a relatively broad base, and standards upon the base arranged to support the ring or band and bottom support at an angle over the base, substantially as described.

This specification signed and witnessed this 9th day of July, A. D. 1902.
